(57) **ABSTRACT**

A new *Chrysanthemum* plant named 'CIDZ0011' particularly distinguished by the red-purple ray floret color, dark yellow-green foliage, excellent flowering uniformity, good branching and a nine week flowering response.

1 Drawing Sheet

1

Latin name of the genus and species of the plant claimed:
Chrysanthemum×morifolium.
Varietal denomination: 'CIDZ0011'.

BACKGROUND OF THE NEW PLANT

The present invention comprises a new *Chrysanthemum*, botanically known as *Chrysanthemum×morifolium*, and hereinafter referred to by the variety name 'CIDZ0011'.

'CIDZ0011' is a product of a planned breeding program. The new cultivar has red-purple ray floret color, dark yellow-green foliage, excellent flowering uniformity, good branching and a nine week flowering response.

'CIDZ0011' originates as a natural whole plant mutation of 'Pink Yosonoma', U.S. Plant Pat. No. 20,547. 'CIDZ0011' was discovered and selected by the inventor as a single flowering plant within a population of the parent cultivar in a controlled breeding program in Fort Myers, Fla., USA in December 2007. The parent cultivar 'Pink Yosonoma' has more of a red-purple ray floret color than that of 'CIDZ0011'.

The first act of asexual reproduction of 'CIDZ0011' was accomplished when vegetative cuttings were propagated from the initial selection in March 2008, in a controlled environment in Fort Myers, Fla., USA.

BRIEF SUMMARY OF INVENTION

Horticultural examination of plants grown from cuttings of the plant initiated in March 2008, and continuing thereafter, has demonstrated that the combination of characteristics as herein disclosed for 'CIDZ0011' are firmly fixed and are retained through successive generations of asexual reproduction.

'CIDZ0011' has not been observed under all possible environmental conditions. The phenotype may vary significantly with variations in environment such as temperature, light intensity and day length.

2

A Plant Breeder's Right for this cultivar was applied for in Canada on Aug. 17, 2010 (10-7069). 'CIDZ0011' has not been made publicly available more than one year prior to the filing of this application.

5 The following traits have been repeatedly observed and are determined to be basic characteristics of the new variety. The combination of these characteristics distinguishes this *Chrysanthemum* as a new and distinct variety.

10 **BRIEF DESCRIPTION OF THE PHOTOGRAPHS**

The accompanying photographic drawing shows typical flower and foliage characteristics of 'CIDZ0011' with colors being as true as possible with an illustration of this type. The photographic drawing shows four flowering potted plants of the new variety, and a close-up of the flowers.

DETAILED BOTANICAL DESCRIPTION

20 The plant descriptions, measurements and aforementioned photographs were taken in Gilroy, Calif. in mid-May 2011 under natural light. These plants were propagated and grown in Nipomo, Calif. and shipped to Gilroy for the data collection and photographs. These plants were approximately 11 weeks of age; grown as four plants together in a six inch pot under greenhouse trial conditions.

25 Color references are made to The Royal Horticultural Society Colour Chart (R.H.S.) 2001.
